UNITED STATES PATENT OFFICE

2,173,030

SEALING AND DISPENSING CAP

Spurgeon White, Trinity, N. C.

Application September 12, 1938, Serial No. 229,600

9 Claims. (Cl. 221—19)

This invention relates to a sealing and dispensing cap.

An object of the invention is the construction of a cap and its cooperating parts in such manner as will cause the cap to be efficiently seated on the container, for the purpose of dispensing liquids.

Another object of the invention is the construction of a container, provided with a peculiar neck, a cap on said neck, and a spring device located within the cap and engaging the neck of the container, whereby the cap is efficiently retained on the neck but is permitted to rotate for dispensing liquids from the container.

A still further object of the invention is the construction of a novel and efficient spring device, interposed between the neck of a container and a cap, for efficiently retaining the cap on the neck in an operable position.

Another object of the invention is the construction of a cap and its cooperating parts, on the neck of a container, the entire device being highly efficient and comparatively inexpensive to manufacture.

With the foregoing and other objects in view, the invention comprises certain novel constructions, combinations and arrangements of parts as will be hereinafter fully described, illustrated in the accompanying drawing, and more particularly pointed out in the appended claims.

In the drawing:

Figure 1 is a top plan view of a device constructed in accordance with the present invention.

Figure 2 is a fragmentary view of a container, shown in elevation, with the cap in vertical section, and the spring device in elevation, on the neck of the container and within the cap.

Figure 3 is a sectional view taken on line 3—3, 40 Figure 2, and looking in the direction of the arrows.

Figure 4 is a sectional view taken on line 4—4, Figure 2, and looking in the direction of the arrows.

Figure 5 is a fragmentary view in elevation of the container, showing the neck portion thereof in vertical section, together with the spring device and the cap.

Figure 6 is a top plan view of the spring device, 50 while

Figure 7 is a perspective view of the same.

Figure 8 is a perspective view of another embodiment of the spring device.

Referring to the drawing by numerals, 1 designates a bottle or container, which is provided

with a neck 2; said neck 2 has a closed top 3. The top of the container has an annular cap seat 4; this cap seat 4 is formed by beveling the top 3. In the top 3 of the container is an outlet 5. This outlet 5 opens upon the cap seat 4. The neck 2 is annularly bevelled at 6. The upper end of the bevelled portion 6 terminates in a horizontal shoulder 7.

A rotatable cap 8 is placed upon the bottle neck 2. This cap 8 is provided with an outlet 9 which is adapted to register with outlet 5, whereby liquid can be dispensed from the container 1. The cap 8 fits snugly against the cap seat 4, and is provided on its lower end with an inwardly extending flange 10. This flange 10 is provided 15 preferably with three small slots 11, for the purpose hereinafter described. The flange 10 fits tightly against the neck 2, Fig. 5.

A spring device 12 is provided for securing the cap on the container. This spring device 12 20 comprises a flat, split, annular body 13; said body 13 has an upstanding sharp lip 14 at one end. The body 13 is also provided with depending integral spring fingers 15. These fingers are separately cut from the body 13. To assemble 25 the spring device 12 with the other parts of the invention, the spring device is slid down over top 3 of the container 1, until the body 13 rests against shoulder 7 (Fig. 5). Then the cap 8 is passed down over the top 3, with fingers 15 riding 30 in the slots 11. Then the cap is in the position shown in Fig. 5, the lower ends of the fingers 15 will be resting upon flange 10, and against the inner face of the cap 8. The upwardly extending lip 14 very tightly engages shoulder 7, so much 35 so that the lip apparently has a digging action on the shoulder, whereby the spring device is retained in a fixed position upon the bottle neck, against rotation, notwithstanding the cap 8 can be rotated satisfactorily by the operator. 40

In the embodiment shown in Figure 8, the spring device 12a is provided with a vertically-positioned annular body 13a. From this body 13a are formed the downwardly extending spring fingers 15a, which operate in the same manner as described for fingers 15 of the spring device 12. On the annular body 13a is also formed an upstanding sharpened lip 14a, which functions similar to lip 14 of the spring device 12. 45

The spring devices shown in Figures 6 and 8 50 are formed from suitable spring metal. Each device is sprung upon the bottle neck, assuming the position as illustrated in Figures 2 and 5.

It is to be noted, Figs. 2 and 4, that the slots 55 11, in flange 10, do not extend the width of the

flange. Therefore, when a spring device is positioned on the bottle neck there is no opportunity for the fingers to pass out thru these slots; in other words, after assembling the parts they are 5 permanently held in position, with the cap fitting snugly upon the container or body.

While I have described the preferred embodiments of my invention and illustrated the same in the accompanying drawing, certain minor 10 changes or alterations may appear to one skilled in the art to which this invention relates during the extensive manufacture of the same and I, therefore, reserve the right to make such alterations or changes as shall fairly fall within the 15 scope of the appended claims.

What I claim is:

1. In a device of the class described, the combination of a container provided with a neck, said neck provided with a shoulder, a rotatable cap 20 on said neck, said cap provided with a flange, said flange provided with slots, a spring device between said neck and said rotatable cap, said spring device bearing against said shoulder, said spring device provided with depending spring 25 fingers, and said spring fingers being adapted to pass through said slots while said cap is being positioned upon said neck, with the outer ends of the fingers resting against said flange, when the cap and neck are assembled.
2. In a device of the class described, the combination of a container provided with a neck, a rotatable cap on said neck, a spring device between said neck and cap and holding said cap in place on said neck, said spring device comprising 30 an annular split body engaging a portion of said neck, said body provided near one end with an up-standing sharp lip engaging said neck, and said body provided intermediate its ends with a plurality of depending spring fingers engaging a portion 35 of said cap.
3. In a device of the class described, the combination of a container provided with a neck, said neck provided with a closed top, said closed top provided on its side with an outlet, said closed 40 top provided with an annular bevelled cap seat and with a horizontal shoulder under said cap seat, a rotatable cap on said neck and resting against said closed top and said cap seat, said cap provided with an outlet being adapted to register with said first-mentioned outlet, said cap 45 provided on its lower end with an inwardly extending flange bearing against said neck, said flange provided with slots at its outer edge, a spring device on said neck within said cap, said spring device comprising an annular body with an upstanding lip engaging said horizontal shoulder, and said annular body provided with depending integral fingers, adapted to pass 50 through said slots on the flange, and seated against the inner face of said inwardly extending flange, substantially as shown and described.
4. In a device of the class described, the combination with a container provided with a neck, of a cap on said neck, said cap being provided 55

on its outer end with an inwardly-extending flange, said flange being provided with spring-finger receiving slots, a spring device provided with downwardly-extending spring fingers between said neck and cap, said spring fingers being adapted to pass through said slots while said cap is being positioned upon said neck, and said spring fingers normally resting upon said flange between said slots.

5. In a device of the class described, the combination with a container provided with a neck, of a cap on said neck, said cap being provided with slots, a spring device holding said cap on said neck and provided with fingers between said neck and cap, said fingers being adapted to 10 pass through said slots while said cap is being positioned upon said neck, and said fingers normally engaging said cap between said slots.

6. In a device of the class described, the combination with a container provided with a neck, said neck provided with a shoulder, of a cap on said neck, a spring device provided with a body engaging only said shoulder, said body provided with fingers extending downwardly beneath said body, and said fingers engaging only at their 15 outer ends said cap.

7. In a device of the class described, the combination with a container provided with a neck, said neck provided with a horizontal shoulder, of a cap on said neck, said cap provided with a flange, a spring device between said cap and neck, said spring device provided with a horizontal body parallel with and engaging said horizontal shoulder, said horizontal body provided with downwardly-extending fingers, and said fingers 20 engaging at their outer ends said flange on said cap.

8. In a device of the class described, the combination with a container provided with a neck, said neck provided with a horizontal shoulder, of a cap on said neck, said cap provided with a flange, a spring device between said cap and neck, said spring device comprising a flat split body parallel with said shoulder and with a portion at the split end engaging the shoulder, said body 25 also being provided with downwardly extending fingers cut from the marginal edges of said body, and said fingers engaging at their outer ends only said flange on said cap.

9. In a device of the class described, the combination with a container provided with a neck, said neck provided with a horizontal shoulder, of a cap on said neck, said cap provided with a flange, a spring device between said cap and neck, said spring device comprising a ring-like split 30 body, said body positioned under said shoulder and provided at the split end with an upwardly extending lip engaging said shoulder, said body also provided on its upper edge only with downwardly extending fingers, and said fingers engaging at their outer ends only said flange on said cap.

SPURGEON WHITE.
